The ornamental designs for an ocular mask, as shown and described.
- DESCRIPTION**
- FIG. 1 is a top perspective view of an embodiment of an ocular mask according to the present designs;
FIG. 2 is a bottom perspective view of the embodiment of FIG. 1;
FIG. 3 is a top-plan view of the embodiment of FIG. 1;
FIG. 4 is a bottom-plan view of the embodiment of FIG. 1;
FIG. 5 is a front elevational view of the embodiment of FIG. 1;
FIG. 6 is a rear elevational view of the embodiment of FIG. 1;
FIG. 7 is a left-side elevational view of the embodiment of FIG. 1;
FIG. 8 is a right-side elevational view of the embodiment of FIG. 1;
FIG. 9 is a cross-sectional view of FIG. 3 taken through line 9-9 of the embodiment of FIG. 1;
FIG. 10 is a cross-sectional view of FIG. 3 taken through line 10-10 of the embodiment of FIG. 1;
FIG. 11 is a top perspective view of a second embodiment of an ocular mask according to the present designs;

FIG. 12 is a bottom perspective view of the embodiment of FIG. 11;
FIG. 13 is a top-plan view of the embodiment of FIG. 11;
FIG. 14 is a bottom-plan view of the embodiment of FIG. 11;
FIG. 15 is a front elevational view of the embodiment of FIG. 11;
FIG. 16 is a rear elevational view of the embodiment of FIG. 11;
FIG. 17 is a left-side elevational view of the embodiment of FIG. 11;
FIG. 18 is a right-side elevational view of the embodiment of FIG. 11;
FIG. 19 is a cross-sectional view of FIG. 13 taken through line 19-19 of the embodiment of FIG. 11;
FIG. 20 is a cross-sectional view of FIG. 13 taken through line 20-20 of the embodiment of FIG. 11;
FIG. 21 is a top perspective view of a third embodiment of an ocular mask according to the present designs;
FIG. 22 is a bottom perspective view of the embodiment of FIG. 21;

FIG. 23 is a top-plan view of the embodiment of FIG. 21;
FIG. 24 is a bottom-plan view of the embodiment of FIG. 21;
FIG. 25 is a front elevational view of the embodiment of FIG. 21;
FIG. 26 is a rear elevational view of the embodiment of FIG. 21;
FIG. 27 is a left-side elevational view of the embodiment of FIG. 21;
